HERBERT W. GUETTLER, OF CHICAGO, ILLINOIS

BARKING APPARATUS AND METHOD

Application filed January 7, 1928. Serial No. 245,065.

My invention relates to a barking apparatus and method.

It is known in the art to bark logs mechanically by having the logs strike against each other or against steel bars in rotating barrels. A familiar example of such an apparatus is the barking drum into which the logs are charged, the drum being rotated to tumble the logs and raise them causing the logs to drop from the upper portion of the drum to the lower portion thereof. In many of these drums the barking is accomplished partly by inwardly projecting ribs against which the logs strike so as to break the bark and loosen it, this bark being rubbed or scraped off of the log. While barking drums have been developed which are efficient in removing the bark from the logs, these drums are open to the objection that they cause splitting and brooming of the log ends resulting in a material waste in pulp wood. This is particularly true in cases where the wood has not been immersed in the water previous to barking and the bark has become dry and adheres to the wood.

With a view to overcoming the above objections various attempts have been made to devise barkers in which the logs are supported in parallel relation in contact with each other and are subjected to a rolling motion. An example of such a barker is disclosed in the patent to C. B. Thorne, No. 1,319,935, issued October 28, 1919. This apparatus employs cams which are rotated and bear against the logs. Due to the superimposed mass of logs, these cams bear against the logs with such great pressure as to cause slivering thereof.

I have found that the above objections can be overcome by using water or other suitable liquid for imparting the necessary motion to the logs, instead of revolving mechanical parts. In accordance with my invention the logs are placed in a vat or tank and by alternately raising and lowering the water level the logs are first floated and then lowered to strike one against the other and form a compact mass or wood pile, this operation being repeated to cause the logs to strike or pound against each other so as to quickly break and loosen the bark. In addition, the body of

water is subjected to a combined pulsating and circulatory motion in such manner as to cause the logs to strike against one another when floating so as to further assist in breaking and loosening the bark, the logs also rubbing against one another so as to quickly rub off the loosened bark. By this method the logs do not strike, and are not struck by, mechanical elements in such manner as to cause splintering or brooming thereof. In practicing my invention the logs are preferably supported in parallel relation and are subjected to transverse movement so that striking of the ends of the logs forcibly against parts of the apparatus used in carrying out my method is avoided. By my method the barking operation may be carried on continuously, the logs being fed into the apparatus at one end thereof as they are discharged at the other end providing an apparatus of large capacity. A further advantage of my invention is that all necessity of employing moving parts of great weight with consequent wear and tear on the apparatus and the requirement of a large power plant is eliminated. Further objects and advantages of my invention will appear from the detailed description.

In the drawings:

Fig. 1 is a central vertical longitudinal view through a barking apparatus constructed in accordance with my invention.

Fig. 2 is a central longitudinal vertical sectional view through a modified form of apparatus, with the piston in its inner position.

Fig. 3 is a plan view of the apparatus illustrated in Fig. 1.

Fig. 4 is a semi-diagrammatic sectional view of an apparatus comprising several units similar to that illustrated in Fig. 2.

Fig. 5 is a semi-diagrammatic sectional view of an apparatus of several units, illustrating a modification of the form shown in Figs. 2 and 4.

In the apparatus illustrated in Figs. 1 and 3, I employ a tank 1 which is of elongated rectangular shape in plan view and is provided with downwardly converging end walls 2 and 3, the inclination of wall 2 being less than that of wall 3, and the upper edge

of wall 2 being in a plane below the upper edge of wall 3. This tank is provided, in the bottom thereof, with a central circular opening about which is secured a ring or flange 4 which projects inwardly beyond the edge of the opening to form a seat for a concavo-convex circular grate 5 which effectively prevents passage of the logs through the opening. A cylinder 6 is secured to the flange 4 by cap screws 7 passing through a flange 8 at the upper end of the cylinder and threading into flange 4. This cylinder has direct communication with the tank through the spaces between the bars of the grate structure 5.

The cylinder 6 is provided at its lower end with an outer annular flange 9 to which is bolted a spider 10 carrying a central bearing sleeve 11 through which operates a piston rod 12 secured to a piston 13 which operates in the cylinder and has a water tight fit therewith. This piston is reciprocated in the cylinder by suitable means connected to the piston rod 12. Any one of several means well known in the art may be employed for reciprocating the piston and it is not necessary to illustrate or describe such means in detail. The tank 1 and the parts associated therewith may be braced and supported by a suitable structure 13, or in any other suitable or preferred manner. An inclined apron 14 is suitably supported on the structure 13 and extends upwardly and outwardly from the upper edge of wall 3 of the tank for directing into the tank logs discharged from an endless feed conveyor 15 of known type driven in a known manner. This conveyor passes about upper sprockets 16 secured on a shaft 17 mounted in suitable bearing blocks 18 which are secured upon elements 19 of the supporting structure 13. The logs 7 discharged from the upper end of the conveyor 15 roll down the apron 14 into the tank 1 which is of a width slightly greater than the length of the logs to be barked. The tank 1 thus provides a suitable container or compartment in which the logs are subjected to the barking operation.

In accordance with my invention, the tank 1 is initially filled with water to the upper edge of wall 2, when the piston 13 is in its innermost or raised position, the water line at this time being indicated by a. When initially setting the apparatus into operation logs are fed into the tank by means of the conveyor 15 until a suitable number of logs are supported by the water within the tank and extending substantially the full length thereof as indicated by dotted lines in Fig. 1. When the proper number of logs have been fed into the tank the piston 13 is reciprocated in cylinder 6. Upon the downward or out stroke of the piston the water flows out of the tank through the grate structure 5 into the cylinder 6 so that, when the piston reaches

its lower-most position, the water level is at approximately the line b and the logs are in a compact mass one upon the other. The cylinder 6 is of large capacity and the piston is reciprocated with sufficient rapidity to cause a quick lowering of the water level upon the downward stroke of the piston thus causing the logs to drop one upon the other. Upon the upward or inward stroke of the piston the water column in cylinder 6 is forced upwardly raising the water level in the tank so as to again float the logs, as in Fig. 2. In this manner the body of water in the tank or log compartment is abruptly and alternately decreased and increased in volume. During reciprocation of the piston the logs are alternately raised and then lowered so as to pound one upon another thus quickly breaking and loosening the bark. This subjects the logs to what is, in effect, a continuous pounding operation. In addition to this, the turbulence of the water caused by the pulsating motion imparted thereto by the piston will cause the logs to strike and rub together when floating in the water. The pounding of the logs against one another is very efficient in breaking and loosening the bark, and the rubbing and striking together of the logs quickly removes the bark from the logs. During this operation the logs are maintained in substantial parallelism and the ends of the logs do not strike forcibly against the tank or any other portion of the barking apparatus. As a result, no brooming or splitting of the logs is encountered, which is highly desirable. As the logs are fed into the tank they travel from the inlet end toward the outlet or discharge end thereof and are discharged over the upper end of wall 2 onto a downwardly inclined grate structure 20 formed of spaced parallel bars supported in a suitable manner by the structure 13. The upper ends of the bars 20a are disposed adjacent a shaft 21 which is rockably mounted in bearing blocks 22 secured to the supporting structure 13.

The condition and characteristics of woods vary, and some logs take longer to bark than others. When logs which are hard to bark are fed into the apparatus, it is necessary to provide means whereby discharge of these logs will be delayed until they are properly barked. This is usually accomplished by slowing down the feed conveyor 15 thus reducing the rate at which the logs are fed into the tank 1, as compared to the rate at which easy barking wood is fed to the tank. However, as it is impossible to adjust the feeding momentarily, I provide means for regulating the discharge of the logs from the tank. Suitable fingers 23 are secured to the shaft 21 and cooperate therewith to form a gate structure. A hand lever 24 is secured on one end of the shaft 21 and is provided with a detent 25 which cooperates with a fixed rack 26

26 for locking the shaft in adjustment. With the hand lever in the position illustrated in Fig. 3, the fingers 23 are disposed vertically and prevent discharge of logs from the tank. 5 Under normal operating conditions, the hand lever 24 is turned into the dotted line position of Fig. 3 disposing the fingers 23 downwardly beyond the bars 20a of the grate structure 20. The logs discharged from the tank 1 roll down the grate structure 20 onto the upper run of an endless conveyor 26 of suitable type, the flexible members or chains of which pass about sprockets 27 secured on a shaft 28 rotatably mounted in bearing blocks 29 secured on sub-frames 30 of the supporting structure 13. This conveyor transfers the logs from the grate structure to storage piles or other apparatus for further treatment. Preferably, a return conveyor (not shown) is provided for returning to the apparatus for further treatment any logs which may be not completely barked, as is known in the art.

The bark which is removed from the logs is discharged over the upper edge of wall 2, and passes between the bars 20a of the grate structure 20 into a hopper 31 supported beneath the grate. The hopper 31 directs the bark into an inclined trough 32 from which it is discharged. A spray pipe 33 is disposed above the grate structure 20, this pipe being provided with perforations which direct a spray downwardly onto the logs to remove therefrom any adhering particles of bark, and onto the grate structure for substantially the full length thereof. The water discharged from the pipe 33 flows into the hopper 31 and thence into the trough 32 washing the bark into and through the trough.

40 In Fig. 2, I have illustrated a modified form of my apparatus in which the tank 1a is provided with an opening 34 extending through the lower portion of its end wall 3a. The tank is further provided with a grate structure 35 extending across this opening, and a rearwardly extending neck 36 provided at its outer end with an annular flange 37. This flange is bolted or otherwise suitably secured to a flange 38 at the forward end of a cylinder 39 in which operates a piston 40. The piston is reciprocated in the cylinder by a piston rod 41 which operates through a guide sleeve 42 of the piston head which may be provided with openings to permit escape of any water which may leak past the piston. 45 In this form of the apparatus the piston is disposed substantially tangentially of the tank 1a and the column of water discharged from the cylinder under pressure impinges upon the mass of logs so as to cause movement thereof toward the wall 2. The operation of the apparatus of Fig. 2 is in all other respects similar to the operation of the apparatus of Fig. 1. In both forms of the apparatus I provide, adjacent the rearward or

inlet end of the tank, a spray pipe 43 having perforations disposed to direct a spray downwardly onto the entering logs and into the tank. This spray serves to replenish the supply of water in tank 1 so as to maintain the water level at the upper edge of the discharge or outlet end of the tank when the piston is in its raised or inner position.

Where found desirable, I may provide a plurality of units arranged in a connected series for successively treating the logs two or more times before final discharge thereof from the barking apparatus. Such an arrangement is illustrated semi-diagrammatically in Fig. 4 in which I have shown three units similar to that illustrated in Fig. 2 disposed in alignment and arranged in successively lower planes, or in stepped relation, the first and second and second and third units being connected by inclined grate structures 20b similar to the discharge grate structure 20. The logs treated in the first unit are discharged therefrom into the second unit where they undergo further treatment, being discharged from the second unit into the third unit in which the barking operation is completed, after which the logs are discharged from this third unit onto the conveyor 26 as previously described.

47 In Fig. 5 I have shown an arrangement similar to that of Fig. 4 but have illustrated a modification of the means for alternately raising and lowering the level of the water in the tank and imparting the previously referred to combined pulsating and circulatory motion thereto. In this form the cylinder 39 of Fig. 2 is replaced by a tubular member or pipe 44 and all of these pipes open into a header 45 at the inner end of a cylinder 46 of proper capacity in which operates a piston 47.

48 The several forms of my invention illustrated all employ the same fundamental idea of causing contact and abrading of the logs, one against the other, by placing them in a body of liquid and imparting relative motion to the logs through the medium of the liquid body exclusively and without the interposition, in the stationary compartment, of any mechanical elements which contact with the logs. A further important feature of my invention is the creation of what may be termed convulsions in the body of liquid in the log compartment by alternately reducing and increasing the volume of such body in appreciable quantity, thus rapidly raising and lowering the level of the liquid in the compartment and imparting the desired motion to the logs. Another valuable feature of my invention is the entire absence from the log compartment of mechanical agitators, barkers, or similar elements. This results in an apparatus of simple and relatively inexpensive construction and high efficiency.

While I have illustrated the several forms of my invention as used for barking logs and have shown comparatively long logs in parallel relation, it will be clear that it can well be used for short logs in helter skelter positions, and for slabs and the like. The terms "log" and "logs" as used herein, and in the appended claims, are not used in their restricted sense, therefore, but are intended to include various wood products and materials such as may be treated in barking apparatuses, and the terms referred to should be so construed.

As above indicated, modifications may be made in my invention without departing from the field and scope of the same and I intend to include all such variations, as fall within the scope of the appended claims, in this application in which the preferred forms only of my invention have been disclosed.

What I claim is:

1. A method of barking logs, consisting in placing the logs to be barked in a liquid 25 in a stationary compartment, and then spasmodically agitating the liquid to cause the logs by contact one with the other to loosen and remove the bark.

2. A method of barking logs, consisting in placing the logs in a stationary compartment with a liquid, and then imparting a pulsating motion to the liquid causing the logs by contact one with the other to break and loosen the bark and to rub together to remove the loosened bark.

3. A method of barking logs, consisting in placing the logs in a compartment, and alternately supplying liquid to the compartment and withdrawing the liquid from the compartment in sufficient quantity to cause the logs by contact to abrade one another to break and remove the bark.

4. A method of barking logs, consisting in placing the logs in a body of liquid, and then imparting a pulsating motion to the body of liquid to cause the logs by contact to abrade one another for loosening and removing the bark.

5. A method of barking logs, consisting in placing the logs in a body of liquid, and then alternately reducing and increasing the volume of the body of liquid causing convulsions thereof, the logs being caused to abrade one another by the convulsions of the body of liquid.

6. A method of barking logs, consisting in placing the logs in a body of liquid, and then alternately withdrawing a quantity of liquid from the body of liquid and returning it to the body of liquid, the amount of liquid withdrawn and returned and the rate of withdrawal and return thereof being of proper value to cause convulsions of the body of liquid, the logs being caused by such convulsions to abrade one another.

7. A barking apparatus comprising a compartment for receiving the logs, and means for forcibly injecting and withdrawing sufficient liquid into and from said compartment to cause the logs to move relatively to and in contact with each other so as to cause them to roll on each other and thereby break up and dislodge the bark. 70

8. In barking apparatus, a compartment for containing a liquid and adapted to receive the logs to be barked, the compartment having downwardly converging walls, and means for alternately and abruptly raising and lowering the liquid level in the compartment, the downwardly converging walls of said compartment promoting rolling and tumbling of the logs in contact one with another incident to variations in the liquid level in the compartment and thereby facilitating loosening and removal of the bark from the 80 85 logs.

9. In barking apparatus, a substantially rectangular compartment for containing a liquid and of a width greater than the length of the logs to be barked, the end walls of the compartment converging downwardly, a cylinder opening into the compartment through one end wall and adjacent the bottom thereof, said cylinder being in free communication with the compartment at all times, and a piston operating in the cylinder, the size of the cylinder and the travel of the piston being of proper value to cause appreciable variation of the liquid level in the compartment, the downwardly converging end walls of the compartment and the injection of the liquid into the compartment from the cylinder and lengthwise thereof, promoting rolling of the logs in contact one with another incident to variations in the liquid level in the compartment and thereby facilitating loosening and removal of the bark from the 90 95 100 logs. 105

10. A barking apparatus comprising a compartment for containing liquid and adapted to receive logs to be barked, a cylinder opening into the compartment below the normal liquid level therein, said compartment being otherwise closed below the normal liquid level, and a piston operating in the cylinder, the volume of the cylinder and the movement of the piston being of proper value to appreciably decrease and increase the volume of liquid in the compartment when the piston is reciprocated, such decrease and increase in volume of the liquid in the compartment causing the logs to contact one another and thereby abrade and remove the bark from the logs. 110 115 120

11. In barking apparatus, a stationary compartment for containing liquid and adapted to receive the logs to be barked, and means for causing the logs to strike and rub one against the other solely by imparting pulsating motion to the liquid so as to break 125 130

and abrade the bark and remove it from the logs.

12. A method of barking logs, consisting in placing the logs to be barked in a liquid in a stationary compartment, and alternately raising and lowering the liquid level in the compartment and thereby causing the logs to strike and contact one another so as to loosen and remove the bark from the logs by abrasion and contact therebetween.

10 13. A method of barking logs, consisting in placing the logs to be barked in a liquid in a compartment, and alternately supplying liquid to and withdrawing liquid from the compartment and in sufficient quantity to alternately raise the logs and lower them into contact with the compartment thereby causing the logs to pound one upon another to break and loosen the bark and remove it from 15 the logs.

20 In witness whereof, I hereunto subscribe my name this 4th day of January, 1928.
